APPARATUS FOR FORMING SHEET METAL ELBOWS

Charles J. Holub, Columbus, Ohio, assignor to
Wheeling Steel Corporation, Wheeling, W. Va.,
a corporation of Delaware

Application October 17, 1936, Serial No. 106,206

3 Claims. (Cl. 153—69.5)

This invention relates to a method and apparatus for making sheet metal elbows and, in particular, stove pipe elbows.

Devices of this general character have been known before, and examples thereof are described and claimed in my prior Patents Nos. 1,517,678 and 1,553,817. The object of this invention is to improve upon the constructions disclosed in said patents, particularly in respect of certain automatic operations such as the clamping of the blank or workpiece in position to be operated upon, and the means applying a brake to arrest operation of the device at intervals.

The improvements in details of construction comprising the present invention are illustrated in the accompanying drawings, and will be completely described hereinafter.

In the drawings,

Fig. 1 is a side elevation;

Fig. 2 is an end view looking from the left in Fig. 1;

Fig. 2A is an elevation of a detail;

Fig. 3 is a view partly in elevation and partly in section along the line III—III of Fig. 1;

Fig. 4 is a central longitudinal section taken through the axis of a mandrel on which the workpiece is disposed for corrugating and bending operations;

Fig. 5 is a sectional view through the mandrel taken along the line V—V of Fig. 4;

Fig. 6 is a side elevation of the parts shown in Fig. 5, looking from the left in the latter;

Fig. 7 is a partial plan view of a clamping carriage movable on the mandrel which is also shown in Figs. 5 and 6;

Fig. 8 is a view partly in elevation and partly in section along the line VIII—VIII of Fig. 5;

Fig. 9 is a partial sectional view along the line VIII—VIII of Fig. 5 but looking in the direction opposite that of the arrows;

Fig. 10 is a partial section along the line X—X of Fig. 5;

Fig. 11 is a view partly in elevation and partly in section along the line XI—XI of Fig. 3;

Fig. 12 is a view partly in plan and partly in section along the line XII—XII of Fig. 3;

Fig. 13 is a partial sectional view along the line XIII—XIII of Fig. 12;

Fig. 14 is an end elevation of a bending ring or head adapted to be placed over the end of the blank to receive the bending force applied thereto; and

Fig. 15 is a plan view of a detail.

Referring now in detail to the drawings, the

apparatus comprises essentially a supporting bed or frame 1 and a mandrel 2 carried thereby on a frame plate 3, the mandrel projecting toward and through an opposed frame plate 4. A carriage 5 slideable on the mandrel 2 and a bending ring 6 cooperate to support a tubular blank 7 therebetween. The carriage 5 is fed forward along the mandrel 2 in a step by step fashion by a ratchet bar 8. Segmental corrugating dies 9 having overlapping ends intermittently form circumferential grooves or corrugations in the blank, and the forward end of the latter is bent upwardly by engagement of bending arms 10 with the bending ring 6. All the parts are operated by a common drive 11 including a clutch 12 and brake 13. Each of these parts will be described in detail under appropriate sub-titles.

The bed and frame

The bed 1 may conveniently be composed of a suitable casting mounted on supporting legs 14. The frame plate 3 is mounted vertically thereon approximately midway between the ends thereof. The plate 4 is similarly mounted adjacent one end of the bed. Spacer rods 3a extend between the plates 3 and 4 adjacent their upper ends. A driveshaft 15 is journaled in a bearing 16 mounted at the end of the bed opposite that on which the plate 4 is mounted, and a bearing 17 formed on the plate 3. A pulley 18 is mounted on the shaft 15 whereby the latter may be driven from any convenient power source. A pinion 19 secured to the shaft 15 meshes with a gear 20 which runs free on a shaft 21 journaled centrally and longitudinally of the bed 1 in bearings 22. A countershaft 23 is journaled along one side of the bed 1 in bearings 24. The shaft 23 is adapted to be driven by the shaft 21 through a gear and pinion drive, the gear thereof being shown at 25.

The mandrel

As best shown in Fig. 4, the mandrel 2 has reduced ends, one of which is firmly seated in a ring 26 pivoted to the plate 3 at 27. A set screw 28 permits the ring 26 to be so tilted as to position the other end of the mandrel accurately. The other end of the mandrel extends through an opening 29 in the plate 4, the reduced end thereof being firmly secured to an anvil ring 30, the function of which will appear later. The carriage 5 includes a member 31 in the form of an annular ring or block slideable on the mandrel 2, being guided therealong by a ratchet bar 8 reciprocable in a suitable slot extending longitudinally of the

mandrel, the bar 8 serving as a feather key for the block or carriage 31. A constant retracting force is exerted on the carriage 31 by a counterweight 33 connected thereto by a cable 34 trained around a pulley 35. The pulley is mounted on a bracket 36 secured to the plate 3.

Semi-circular clamping jaws 37 are pivoted to the carriage 31 on a pin 38. These jaws have shoulders 39 which enter an annular groove 10 formed in the carriage, and are normally urged apart by a compression spring 40, the ends of which are seated in sockets 41 formed in the abutting ends of the jaws. The jaws 37 have depending lugs 42 through which a cam shaft 43 extends. 15 A cam 44 adjustable on the shaft 43 is adapted to cooperate with a fixed cam 45 on the depending lug of one of the jaws whereby to cause the jaws to contract on rotation of the shaft. A lever 46 secured to the shaft 43 causes the latter to turn 20 to contract or release the jaws.

A slide 47 is movable in guides 48 mounted on the side of the carriage 31. The slide has a pin and slot connection 49 with the lever 46. The lever 46 is automatically operated on advance 25 and retraction of the carriage 31 in a manner to be explained in greater detail later.

As best shown in Fig. 4, an end of the tubular blank 7, which may be formed up into a cylinder from flat stock by any convenient means (not 30 shown), is inserted in the annular space between the clamping jaws 37 and the reduced end of the carriage 31 indicated at 50. The bending ring 6 is slipped over the other end of the blank.

35 Work-feeding mechanism

The ratchet bar 8 cooperates with a pawl 51 to advance the carriage 31 step by step from the solid line position, in which it is shown in Fig. 4, to the position shown in dot and dash lines. The 40 bar 8 is reciprocated periodically by means to be described later through a distance equal to the pitch of the ratchet teeth thereon. The cooperation of the pawl 51 with the ratchet teeth causes the carriage 31 to move forward with the bar 8. 45 The outer end of the blank 7 slides over the anvil ring 30 as the carriage 31 is advanced. The friction between the ring 30 and the blank and between the carriage 31 and the mandrel prevents the latter from moving back with the bar 8. 50 On backward movement of the latter, the pawl slides in a vertical slot in the carriage 31 and then engages the next tooth. The counterweight 33 exerts a restraining force on the carriage 31 to prevent it from being advanced more than one 55 step at a time, and to ensure close engagement between the pawl and the ratchet teeth, to position the work accurately for the corrugating operation.

A link 53 is pivotally mounted in a bearing 60 bracket 54 carried on top of the carriage 31. A lever 55 is pivoted to the link 53, and a detent 56 is pivoted to the lever 55. The detent 56 has a hook 57 normally engaging one end of the link 53. The detent 56 also has an inclined surface 65 58 adapted to cooperate with an abutment 59 on the plate 4 having a similar surface. A spring latch 60 is carried on the lever 55. At its lower end, this latch has a projection capable of engaging under a cooperating projection on the pawl 70 51 to hold the latter in elevated position. With the parts in the position illustrated in Fig. 4, however, a stud 61 is engaged by the latch 60 to cause the latter to release the pawl 51. When the carriage 31 has been moved forward to the position 75 shown in dot and dash lines, engagement of

the surface 58 of the detent 56 with the abutment 59 tilts the lever 55 and places the latch 60 in position to hold the pawl 51 in elevated position. After the pawl has been raised in the manner indicated, no further forward movement of the carriage 31 is effected despite continued reciprocation of the bar 8. The abutment 59 and the detent 56 thus operate as an automatic stop mechanism for the step by step feed of the carriage 31.

A stud 62 is adapted to engage the slide 47 to contract the clamping jaws 37 when the carriage 31 is in the position shown in solid lines in Fig. 4. A stud 63 engages the slide 47 as the carriage 31 approaches the plate 4, to cause the clamping jaws to be released.

The mechanism for reciprocating the bar 8 includes a lever 32a connected to the end of the bar 8 by a link 32b. The lever 32a is pivoted at 32c on the plate 3. A cam follower 32d is also pivoted to the plate 3 at 32c, and has a roller 32e at its lower end which traverses a groove in a barrel cam 32f carried on the shaft 21. The link 32a has a projection 32g extending into a slot intermediate the ends of the follower 32d. Set screws 32h permit adjustment of the lever 32a relative to the follower 32d, whereby the desired movement of the ratchet bar 8 may be obtained.

15 The corrugating dies

The blank 7 is corrugated and bent as it advances over the anvil ring 30. This ring has a circumferential groove 64 which is wider adjacent the bottom of the ring than at the top thereof. The corrugations in the blank are thus more closely compressed on the inner side of the elbow 35 than on the outside since, as indicated in dot and dash lines in Fig. 4, the emerging end of the blank is bent upwardly to form the elbow. The corrugations formed on the outside of the bend are slightly flattened or drawn out by the bending 40 in operation.

The corrugating dies 9 are carried on slides 65 (Fig. 2A) which are movable on the plate 4 radially of the circular opening 29 therein. The slides 65 are carried between segmental dovetail 45 guides 65a formed on the outer side of the plate 4. Reciprocation of the slides 65 is effected by an annular rim 66. The ring 66 is rotatably carried by roller bearings 67 spaced about the plate 4, and is held against movement away from the plate by keepers 68. The keepers are secured by screws to studs 69 mounted on the plate 4. The ring 66 has hardened inserts 70 spaced there-around for engagement with the roller bearings 67.

Cam slots 71 are formed at intervals around the ring 66. The outer sides of these slots are provided with hardened inserts 72. The slides 65 have roller bearings 73 thereon extending into the slots 71. By reason of the construction described, counterclockwise rotation of the ring 66 will cause inward radial movement of the slides 65. Clockwise rotation of the ring 66 will cause outward radial movement of the slides. Such back and forth rotary movement of the ring 66 is provided by a crank arm 74 attached thereto, an adjustable link 75 and an eccentric 76 on the shaft 23.

The oscillation of the ring 66 and the reciprocation of the ratchet bar 8 are timed so that the corrugating dies move inwardly as the ratchet bar is retracted, the corrugating dies being withdrawn when the ratchet bar is advanced to feed the work.

Bending arms

Bearing brackets 71 are carried at the working end (the left end, as shown in Fig. 1) of the apparatus, and a shaft 78 is journaled therein. The ends of the shaft are flattened, as shown in Fig. 5. The bending arms 10 are pivoted at 79 on the flattened ends of the shaft. The holes in the arms 10 through which the flattened ends of the shaft extend are relieved as at 80 to permit the arms 10 to tilt on their pivots 79. Tension springs 81 extend between brackets mounted on the shaft 78 and brackets secured to the lower ends of the arms 10 for normally holding the arms in the position illustrated in Fig. 2.

15 The arms 10, on oscillation of the shaft 78, are adapted to engage lugs 82 formed on the bending ring 6. Such engagement causes the bending ring 6 to be deflected upwardly as successive corrugations are formed in the blank 7, as indicated in dot and dash lines in Fig. 4.

20 Oscillation of the arms 10 is effected by a downwardly extending link 83 keyed to the shaft 78. A tension spring 84 normally urges a set screw 85 at the lower end of the link 83 into engagement with a slide 86 axially movable in a guide 87 carried in the bed 1. The slide 86 has a roller 87a projecting into a slot 88 formed in a barrel cam 89 on the shaft 21. The oscillation 25 of the arms 10 is thus co-ordinated with the reciprocation of the forming dies 9 and the feed bar 8.

Driving clutch and brake

30 The parts already described are operated by the common drive 11 under the control of the clutch 12 and the brake 13. A hub or block 90 keyed to the shaft 21 has an axial slot 91 in which a slide 92 is movable. A spring 93 seated behind the slide 92 normally tends to move the latter to the left, as viewed in Figs. 11 and 12. The gear 19 has a hub provided with driving faces 94 adapted to engage the slide 92, as indicated in Fig. 13, whereby clockwise rotation of the gear 19 drives the hub 90 on engagement of the slide 92 by one of the faces 94. Between the faces 94, the hub is provided with sloping surfaces 95. Since the slide 92 is normally forced toward the gear 19, the latter is normally in driving relation with the hub 90 through which the shaft 22 is driven.

35 A link 96 pivoted to the bed at 97 is so disposed that its free end may be moved into the space between the hub of the gear 19 and the hub or block 90. The end of the link 96 is rounded as at 98 for cooperation with a similarly shaped surface 99 on the slide 92. If the link 96 occupies the position shown in Fig. 3, engagement of the surfaces 98 and 99, as the hub 90 rotates clockwise, will cause the slide 92 to be forced back into the recess 91, thereby freeing the hub from driving relation with the gear 19. Rotation of the latter continues thereafter without effect on the hub 90, until the free end of the link 96 is raised to permit the slide 92 to be moved back to the position indicated in Fig. 12. The next engagement between one of the driving faces 94 of the gear 19 and the slide 92 will cause the hub 90 to move again with the gear 19.

40 The link 96 is operated from a rock shaft 100 through a linkage including links 101 and 102. The link 96 tends to fall by its own weight to the position shown in Fig. 3 in which it causes disengagement of the hub 90 from the gear 19 in the manner already described. It may be raised

45 to permit resumption of the driving relation by tilting the rock shaft 100. The rock shaft 100 is journaled in suitable bearings in the plates 3 and 4, and is provided with a cam block 103. A slide 104 is mounted in bearings 105 on the plates 3 and 4 for longitudinal movement. An operating handle 106 is secured to the slide 104. A cam block 107 is adjustably mounted on the slide 104 for cooperation with the cam block 103. Movement of the slide 104 to the right as viewed in Fig. 1, by cooperation of the cam blocks 103 and 107 causes counterclockwise rotation of the rock shaft 100, as viewed in Fig. 3, to raise the link 96. This movement also operates to release the brake 13 to permit free rotation of the hub 15 90 with the gear 19.

50 The brake 13 comprises a yoke 108 embracing the hub 90. The yoke is pivoted to the bed 1 at 109 and is split at a diametrically opposite point to permit contraction thereof for gripping the hub 90 in the manner of a friction brake. The adjacent ends of the yoke, indicated at 110, are normally urged apart by a spring 111 seated in aligned bores therethrough, and backed up by a screw plug 112. The ends 110, however, may be caused to approach each other by a camming lever 113. A stud 114 is threaded into the lower end 110 of the yoke, is freely movable through a hole in the other end 110, and has a pivotal connection 115 with the lower end of the camming lever 113. The lower end of the lever 113 is bifurcated and extended to provide toes or camming surfaces 116 engaging the upper end 110 of the yoke 108. When the lever 113 is rotated about the pivot 115 clockwise, as viewed in Fig. 35 11, the ends 110 of the yoke will be forced together, and the body of the yoke will be sprung sufficiently to grip the hub 90. Reverse rotation of the lever 113 will permit the spring 111 to release the gripping engagement of the yoke 108 40 on the hub 90.

45 The lever 113 is operated simultaneously with the rock shaft 100 from the slide 104. A link 117 is pivotally mounted on a bracket 118 carried on the plate 3, and is pivotally connected to the end of the slide 104 which extends therethrough. The lower end of the link 117 is pivotally connected to the lever 113 by a link 119. Movement of the slide 104 to the right, as viewed in Fig. 1, thus causes the brake to be released and the clutch engaged. Reverse movement of the slide causes disengagement of the clutch and engagement of the brake. The connection between the link 119 and the lever 113 is provided by a pin and slot 119a providing a small amount of lost motion. The amount of this lost motion may be adjusted by a set screw 119b carried on a lug depending from the link 119. By reason of this lost motion, the brake 13 is not applied until an instant after the clutch has been disengaged, 60 the sequence being, first, the disengagement of the clutch and, after a very short interval, the application of the brake to stop the shaft 21. The inherent resilience of the yoke 108 causes the brake to be released as soon as the lever 106 65 has been moved to the right to cause engagement of the clutch.

The operation of the device

70 The carriage 31 occupies the position indicated in dot and dash lines in Fig. 4, at the commencement of an operating cycle. One end of the tubular blank 7 to be corrugated and bent is first inserted in the annular slot in the bending ring 6. While the blank may be formed in any con- 75

venient manner, bending rolls (not shown) may well be driven by a shaft 120 which is driven by a belt and pulley drive from the shaft 21, as shown in Fig. 2. The shaft 120 is journaled in bearings supported on angles 121 extending laterally from the bed 1. The blank is inserted in the ring 6 so that the lap joint is adjacent an index mark 122 on the ring 6 (see Fig. 14). The other end of the blank may then be inserted between the clamping jaws 37, which are opened as a result of the engagement of the stud 63 with the slide 47. The ring 6 carries a guide tongue 123 adapted to cooperate with a guide plate 124 having a slot 125 therein, one end of the slot being tapered, as at 126, to guide the tongue 123 entering therewith. The plate 124 is mounted on top of the bearing bracket 71, as shown in Fig. 2. As the blank is pushed back over the mandrel 2, forcing the carriage 31 to the right, as viewed in Fig. 4, the tongue 123 is guided into the slot 125 to position the lap joint in the blank accurately on the inside of the bend to be formed therein.

When the carriage 31 is pushed back to the position illustrated in solid lines in Fig. 4, the stud 61 depresses the spring latch 60 to release the pawl 51. The stud 62 automatically causes the clamping jaws 37 to grip the end of the blank inserted between them and the end of the carriage 31. Needless to say, the corrugating dies 9 should be retracted before it is attempted to insert the blank into the machine. As the bending ring 6 approaches the arms 10 during the insertion of the blank into the machine, the lugs 82 engage divergent wings 127 extending outwardly from the arms. Advancement of the ring 6 causes the arms 10 to shift outwardly on their pivots 79 to permit the ring to pass therebetween. After the ring has passed to arms, the springs 81 restore them to their normal position in which they cooperate with the lugs 82 to bend the emerging blank.

The machine may be started by pushing the lever 106 to the right. This raises the lever 96 and permits the clutch 12 to become engaged by advancement of the block 93 into such position as to be engaged by the driving surfaces 94. The brake 13 is simultaneously released as already explained. Intermittent operation of the forming dies 9, bending arms 10 and ratchet bar 8 proceeds in such co-ordinated fashion as successively to form corrugations, bend the emerging end of the blank, compressing the corrugations on the inside of the bend and flattening or stretching those on the outside, and then notch the blank forward for repetition of these operations. When the required number of corrugations and bending impacts have been applied, the carriage 31 approaches the plate 4 and the detent 56 engages the abutment 59 to place the spring latch 60 in the position to engage and hold up the pawl 51. Engagement of the stud 63 by the slide 47 causes the latter to shift and release the clamping jaws 37. The clutch may then be disengaged and the brake engaged by moving the handle 106 to the left, although failure to do so will not result in any damage, as the feed means is rendered ineffective by the latch 60. While operation of the corrugating dies and the bending arms 10 continues until the handle 106 is shifted, such operations will produce no effect in the ab-

sence of a forward feed of the workpiece. The completed elbow may then be removed from the carriage 31 and, if desired, the lap joint riveted. The bending ring 6 is removed from the blank and the machine is then ready for a repetition of the operating cycle just described.

It will be apparent from the foregoing description that the invention is characterized by numerous features of novelty and advantage compared to devices of this character which have been known heretofore. The construction of the mechanism for operating the corrugating dies is simple, sturdy and rugged, and therefore not likely to cause difficulty in operation. The automatic clamping for engaging the end of the blank first inserted in the machine is highly effective to hold the blank in proper position during the fabricating operation, since it engages the blank substantially throughout the circumference of the latter, and release it in ample time for quick removal. The brake operation is automatically co-ordinated with the operation of the clutch to stop the machine instantly when the clutch is disengaged, preventing continued operation by the momentum of the rotating parts. The adjusting means included in the linkages operating the ratchet bar and the corrugating dies permit the several steps of the operation to be timed accurately so there will be no interference or overlapping of operations.

Although I have illustrated and described but one preferred embodiment of the invention, it will be recognized that changes in the construction disclosed may be made without departing from the spirit of the invention or the scope of the appended claims.

I claim:

1. In an elbow forming machine, having a mandrel, a carriage reciprocable thereon adapted to receive one end of a tubular blank to be formed into an elbow, a reciprocable ratchet bar and a pawl on said carriage cooperating therewith whereby to advance the carriage step by step; a lever tiltably mounted on said carriage, a second lever pivoted thereto, a detent pivoted on the second lever and releasably engageable with the first, a pawl-holding latch on said second lever and means engaged by said detent on movement of the carriage to its extreme forward position, to trip said detent and disengage the first mentioned lever, whereby to tilt both said levers and thereby move said latch into pawl engaging position.

2. The apparatus defined by claim 1 characterized by means for resetting said levers and releasing said latch on movement of the carriage to its extreme rearward position.

3. In an elbow corrugating and bending machine having feed, corrugating and bending means, a drive for said means including a clutch, and a brake; a lever for operating said clutch and a lever for operating said brake, said levers being pivoted on axes at substantially right angles, and common means for actuating said levers comprising a slide bar linked to one lever, a rock shaft parallel to said bar and having a crank thereon, means connecting the crank to the other lever and cooperating means on the slide bar and rock shaft to cause rotation of the latter on reciprocation of the former.

CHARLES J. HOLUB.
